UNITED STATES PATENT OFFICE.

ALBERT C. WOODWORTH, OF PROVIDENCE, RHODE ISLAND, ASSIGNOR TO
THE CONSOLIDATED CAR FENDER COMPANY, OF SAME PLACE.

DESIGN FOR A GUARD OR CUSHION FOR STREET-CARS.

SPECIFICATION forming part of Design No. 27,656, dated September 21, 1897.

Application filed March 10, 1896. Serial No. 582,656. Term of patent 14 years.

To all whom it may concern:

Be it known that I, ALBERT C. WOODWORTH, of the city and county of Providence, and State of Rhode Island, have invented and produced a new and original Design for a Guard or Cushion for Street-Cars, of which the following is a specification.

The leading feature of the design consists in a guard or cushion of grid-like structure having a substantially straight portion at one side and having a recurved portion at the opposite side.

The design is illustrated in the accompanying drawing, in which the figure is a perspective view of a car-fender provided with a guard or cushion embodying the design.

In the drawing the guard is shown secured to a pilot member; but said guard may be otherwise used, as by securing the same to the end of the car.

A is the pilot member, composed of rods and secured in the cross-bars $a'a'$, and secured at their front ends to the cross-rods a^2 .

B is the guard or cushion embodying the present design, and is constructed of strips b , secured at one end to a cross-strip b' , extending from said strip in a substantially straight line and being secured at their opposite ends and secured to a cross-strip b^2 . The strip b^2 may be curved slightly to add to the graceful appearance of the guard, and the strips b' and b^2 may be connected by the end strips b^3 . b^4 is a cross-strip secured to the strips b .

The design provides an attractive and graceful guard or cushion which presents a characteristic and distinguishing appearance to the eye.

What I claim is—

The design for a guard or cushion substantially as shown and described.

ALBERT C. WOODWORTH.
